United States Patent Office.

HENRY WHITTEMORE, OF NEW YORK, N. Y.

Letters Patent No. 96,523, dated November 2, 1869,

IMPROVED ORNAMENTAL COVERING FOR FLOORS, WALLS, &c.

The Schedule referred to in these Letters Patent and making part of the same.

To all whom it may concern:

Be it known that I, HENRY WHITTEMORE, of New York, in the county of New York, and State of New York, have invented a new and useful Improvement in Ornamental Wood Covering for Floors, Walls, &c.; and I do hereby declare the following to be a full, clear, and exact description of the same, reference being had to the accompanying drawings, in which—

Figure 1 represents, in perspective, the interior of a room decorated with the floor and wall-covering which I have invented.

Figure 2 represents a square or corner-piece, showing the manner of combining the various pieces.

Figure 3 is an edge view of the same, showing the canvas back.

For convenience, I hereinafter describe my invention as applied to floors, but I do so only for convenience, as it may be applied in the same way to walls, wainscots, ceilings, stairs, &c., and I desire to be understood as including all of these uses in my description.

In wooden marquetry floors it has hitherto been customary to employ wooden pieces of about oneinch in thickness, and to fit the various parts upon the floor, itself, separately securing each piece in place. This process is expensive and tedious, and my invention is designed to produce the same effects at a much less cost.

It consists in forming the marquetry design with thin strips of different woods, cut and fitted at the workshop, and with glue or other cement securely set in place upon a backing of canvas or other suitable material. By this method the floor-covering is entirely prepared and finished at the workshop, where proper machinery can be employed to facilitate and perfect the work. It may then be conveyed to the place of deposit and laid upon the floor with as little trouble as ordinary carpet or oil-cloth, being secured in place by a few slender nails.

That others may fully understand this invention, I will particularly describe its construction and advantages.

The wood to be employed should be thoroughly seasoned by kiln-drying or otherwise, and, after being slotted into laths about one-fourth of an inch in thickness, and of about one inch in width, more or less, it is smoothly planed and the edges matched.

These lath are then cut by pattern to fit the desired

ornamental marquetry figures, are properly arranged within suitable compressing-frames, and their edges firmly bound together. Glue or other suitable cement is then spread over the surface of a piece of suitable canvas or other fabric, and the same is then laid upon the wood and firmly compressed thereto, so that, when dry, the pieces forming the design, are all firmly bound in place upon the canvas back.

The wood side is then planed, smoothed, and polished, and is ready to be laid upon the floor.

A floor-covering constructed in this way is materially cheaper, not inferior in any respect to that made of thicker wood in the ordinary way, and in some particulars it is actually much superior to the ordinary marquetry flooring.

It is much cheaper, first, because it consumes only about one-third as much material; second, it affords facility for the use of machinery; third, the actual labor of placing and securing the blocks is considerably less.

It is equally durable, because, before the thickness of this flooring will have been worn through, any flooring would require to be relaid.

It is superior, from the fact that there will never be any open cracks to harbor dust or vermin, and the canvas backing forms a superior deafener.

Hence, for office, stair-passage, and hospital-floors, it forms a most desirable covering; and, on account of the beautiful combinations and designs it is susceptible of, it is also particularly adapted to use in parlors and dining-rooms, in lieu of mattings, oil-cloths, &c.

For use as wainscoting, it is secured against the wall by rebating the wash-board, and by proper nosing, &c., at the upper edge.

This invention may also be applied to the purposes of decoration of articles of furniture, in panelling, &c., and in the construction of boxes, &c., for which it is intended to ask for separate Letters Patent.

Having described my invention,

What I claim as new, is—

Marquetry floor and wall-covering, constructed by cutting and fitting thin pieces of wood, and gluing them to a back of canvas or other suitable material, substantially as set forth.

HENRY WHITTEMORE.
